UNITED STATES PATENT OFFICE

2,444,236

PORTABLE EXTENSION FOR BAG RACKS

Monroe E. Williams, Oakland, Calif.

Application July 16, 1945, Serial No. 605,351

8 Claims. (Cl. 211—12)

1.

The invention relates to the construction of racks, employed to support bags or other such containers, in position to be filled, and has particular reference to the bag-supporting racks with which railway mail cars are equipped.

An object of the invention is to provide a readily securable device of the character described by means of which the bag capacity of such a rack, beyond its normal rating, may be regulated as desired.

Another object of the invention is to provide a bag rack extension of such design that a large portion of the apparatus presently used, and constituting a comparable rack extension, has been dispensed with.

A further object of the invention is to provide a bag rack extension which, as a result of its simplicity and compactness, permits it to be stored when not in use in a minimum of space.

Still another object of the invention is to provide improved construction for bag racks of the type referred to which dispenses with the need for vertical secondary support members, rising from the floor over which the rack may be positioned, together with the usual mounting devices generally associated with such support members.

Yet another object of the invention is to provide an attachment for extending the capacity of bag racks, which is constructed as an integral unit, is marked by sturdiness of design and embodies no detachable parts which may become displaced or separated from the device during use or storage thereof.

A further object of the invention is to provide an extension of the character described purposely designed to be detachable from the main rack so that when not in use it will not interfere with the free movements of the operator nor adversely affect his work efficiency.

Still another object of the invention is to provide an extension for bag racks which may be mounted and dismounted without the manipulation of any latching or other holding means to secure the extension in place on its support.

Another object of the invention is to provide in a bag rack extension of the nature above described, novel means for mounting the extension on the main rack wherein gravity serves to hold the extension in place and only abnormal movement, which is not encountered in normal use, is necessary in order to detach it from its support.

A further object of the invention is to provide, in an extended rack for supporting a plurality of bags or other such containers and which is used

2.

in conjunction with a working surface or table carried by and adapted for selective location between the ends of the rack, an extension for supporting auxiliary bags or the like adapted to be positioned at selected locations between the ends of the rack, or in locations straddling the ends of adjacent racks, and in predetermined relationship with the working surface or table.

Another and important object of the invention is to provide an extension unit for bag racks which effects a conservation of floor space by affording a wider passageway between confronting rack units than can be obtained with the type of rack extension in present use.

15 The invention possesses other objects and features of value which, together with the foregoing, will be specifically pointed out in the detailed description of the preferred form of the invention hereunto annexed. It is to be understood that the invention is not to be limited to the specific form thereof herein shown and described as various modifications thereof may be employed within the scope of the appended claims.

Referring to the drawings:

25 Figure 1 is a top plan view of a complete bag rack unit and a portion of an adjacent unit; the latter being broken off so as to shorten the view.

Figure 2 is a vertical sectional view of the structure shown in Figure 1, the plane in which the view is taken being indicated by the line 30 2—2 of the latter figure. The dotted and dot-dash lines indicate, respectively, the folded position of the main rack unit and the position of a bag carried by the extension unit.

Figure 3 is a view, similar to Figure 2, showing the position of the distributing table and its relationship to the rack structure.

Figure 4 is a perspective view of the rack extension unit.

The present type of bag rack in general use in railway mail cars comprises a plurality of brackets 6 which are secured to the bulkhead or inner side wall 7 of the car in horizontally aligned and spaced relationship at the required distance above the floor 8 of the car. Each of the brackets 6 is bifurcated and is fitted with a removable block 9 held in place by a bolt 11 passing through the block and through both side members of the bracket. There is thus formed in each bracket an aperture which receives and journals a section of pipe 12 having an overall dimension sufficient for the length of rack desired and commonly known and designated in the art as No. 1 rod. Secured to the ends of the pipe 12 are end members 50 or arms 13 which, in their operative position

mutually lie in substantially a horizontal plane and extend generally in a direction outwardly from the bulkhead or sidewall 7. Each end member or arm 13 is provided at its extreme end with a pair of vertically spaced apertured eyes 14 and 16 and medially of its ends with a similar pair of apertured eyes 17 and 18. Pipes 19, 21 and 22, which are similar to the pipe 12, have their ends secured in the eyes 14, 16 and 17 respectively and parallel each other, the pipes 19 and 22 being axially equidistant and the pipe 21 being spaced slightly outwardly, with respect to the bulkhead or wall 7, from the pipe 19. The pipes 22, 19 and 21, respectively, are commonly known and designated in the art as No. 2 rod, No. 3 rod and No. 4 rod. Interposed intermediate each end member 13 and the floor 8 is a leg or strut, which supports the end member in its aforesaid substantially horizontal position, comprising a pair of telescopic tubes 23 and 24, the tubes being relatively slideable axially of each other. The upper end of the outer tube 23 is fitted with a plug member 26 clevised to receive the eye 18 and pivotally connected thereto by means of a pin or bolt 27. The lower end of the inner tube 24 is fitted with a similar plug 28 pivotally engaged, by means of a pin or bolt 29, with a bracket 31 secured to the floor 8. The length of the outer tube 23 is such that when its lower end impinges against the shoulder 32 of the plug 28 the end member will be properly positioned relative to the floor.

Each of the pipes 12, 22 and 19, comprising rods Nos. 1, 2 and 3, are provided as best shown in Figure 1 with sets of hooks arranged to engage the rim grommets of bags indicated by the dot-dash lines 33, the bags being thus supported in depending position by the rack. At the rearward side of each bag is positioned a label carrier 34, which may be viewed from the operational side of the apparatus, represented by the bottom of the drawing, attached by suitable means to the pipes 12, 22 and 19. When devoid of bags 33 the rack section may be pivoted upwardly about the axis of the pipe 12 to a position, indicated by the dotted lines of Figure 2, wherein the pipe 22 engages one or more latch dogs 36 which are pivotally mounted on the bulkhead or sidewall 7 by brackets 37. The fold-up feature of the rack permits it to be moved out of the way in the event that the car is to be cleaned or used for transportation purposes in which there is no need for the bag racks.

The apparatus so far described comprises a standard rack unit which is usually adapted to support ten full-size mail bags. Where the capacity of the rack is to be increased to accommodate a large number of bags, extensions known as bridges are employed. Each of these bridges comprises a rectangular pipe frame of a size sufficient to accommodate two bags and as many as desired of the bridges are attached to the main rack, along the inboard or working side thereof to provide the desired increased capacity. Connection is effected by a pair of hooks each being engaged with the pipe or No. 4 rod 21. The opposite side of the bridge is equipped with a similar pair of hooks extending downwardly to releasably engage one of a pair of parallel center rods extending in spaced relation with and completely across the front of the main rack unit. The opposite ends of each pair of center rods are tied together by and secured to links each of which is provided with a downwardly-extending stem adapted to releasably engage one of a pair of sockets formed in the upper end of a pedestal

rising from the car floor, the base of the pedestal being releasably attached, by suitable bolts and wing nuts to a base plate permanently located and secured in the car floor. Such pedestals are provided at the opposite ends of each section of center rod and at the junction between adjacent sections thereof in which case the grouped stems of the links of the abutting center rod sections occupy both of the pedestal sockets.

In addition to the extension bridges a demountable distributing table is provided, which extends across substantially one-third of the total length of the rack sections, which is used for supporting the material, such as mail, which is to be selected and deposited in the respective bags. The manner of supporting the distributing table is similar to that employed in mounting the bridge unit and comprises a pair of hooks secured to the bottom of the table, which releasably engage one of the center rods, and an additional pair of hooked arms pivotally mounted adjacent the edge of the table facing the bulkhead or side wall of the car and adapted to releasably engage the pipe 21 or No. 4 rod. Both the bridges and the distributing table are interchangeable so that the order of their relationship across the front of the complete rack unit may be altered as desired or arranged to afford a more advantageous position for the operator.

It will be seen, from the description thus far, that the presently used apparatus for extending the capacity of bag racks comprises a large number of extra parts which are rather complicated in structure, which require considerable time to set up and remove and which occupy a comparatively large volume of storage space when the rack extensions are dismantled and not in use. I have succeeded in evolving an improved rack extension which renders it unnecessary to use the present center aisle equipment, namely, the permanent floor plates for the center rod pedestals, all of the pedestals, the center rods and their connectors and the more or less cumbersome present type of bridge together with all of the hook devices used in mounting the bridges on the main racks and center rods. As is best shown in Figure 4, I provide substitute bridge units each comprising a pair of side bars 38 joined by parallel pipes or rods 39 and 41 which are secured, at their respective opposite ends, in eyes 42 and 43 provided at what will be termed the outer end of each arm. The position of the eyes 43, which are formed at the terminals of angular extensions 44 of the side bars 38, with relation to the eyes 42 is such that it is the same axial spacing and angular positioning of the pipes 39 and 41 as exists between the pipes 19 and 21. The opposite or what may be termed the inner end of each side bar 38 is provided with vertically spaced notches 46 and 47, the uppermost notch 46 being positioned at the extreme end of the side bar and opening in a generally vertical direction and the lowermost notch 47 being formed in a lug 48 projecting from the lower edge of the side bar and opening in a generally downward direction which is angularly related to the direction of opening of the notch 46. Bag hooks 49, in sufficient number to support three full-size mail bags, are arranged in suitable spaced relationship on and along the pipe 39, these hooks being standard equipment similar to those used on the main rack units. The mutual relationship between the notches 46 and 47 is identical with that which exists between the pipes 19 and 21 and between the pipes 39 and 41 so

as to conform with standard equipment design and dimensions. In Figures 2 and 4 the method of attachment of the extension unit to the front of the main rack may best be observed. As will be seen, the notches 46 and 47 engage the pipes 19 and 21 respectively and the operation of disconnecting the unit from the main rack consists of lifting the front end of the unit in a pivotal movement about the axis of the pipe 19 until the pipe 21 is completely dislodged from the notch 47, whereupon the inner end of the unit may be dropped so as to dislodge the pipe 19 from the notch 46. Attachment of the unit, of course, entails a repetition of the foregoing operations in reverse order. It will be noted that the particular arrangement of the notches, forming the mounting means for the extension units, provides the condition wherein the weight of the unit itself plus any additional vertical load which may be imposed on it serves to securely seat the pipes in the respective notches. It follows that accidental disconnection of the extension units from the main rack is highly improbable since the considerable upward movement necessary in order to free the pipe 21 from the notch 47 is not usually encountered in the normal use of the device.

It will be also noted that the vertical position of the extension relative to the main rack is such that a standard bag 51 hanging from the extension unit hooks 49 is designed to rest on the floor 8. Thus the weight of any material placed in the bag will be borne by the floor and only a portion of the weight of the bag plus any slight pressure, which tilting of the stacked material contained in the bag will create, will be imposed on the extension unit, its mounting connections and the pipes 19 and 21.

Redesigning and simplification of the distribution table 52 and its supporting structure has also been accomplished as will be seen by reference to Figure 3. The front edge of the table is provided with the usual standard hooks 53, which releasably engage the pipe 14 of the main rack unit, and one or more legs 54, depending on the overall length of the table, are pivotally mounted by means of brackets 56 on the underside of the table adjacent its front edge. The legs, when the table is in use, rest on the floor 8 as shown and are fitted with articulated link braces 57 which prevent collapsing of the leg under the table should the leg be accidentally kicked by an operator in passing along the passageway. When it is desired to detach the table for storage the legs 54 may be folded up underneath the table so as to reduce to an efficient minimum the bulk of the unit.

In Figure 1 it will be seen that the three bags carried by the extension unit are arranged in file order across and parallel with the front of the main rack as compared with the standard practice of arranging the two bags of the present extension bridge in file order transversely of the length of the main rack. The improved structure of the invention therefore actually increases, the passageway in front of the extended rack and in such a congested location as a railway mail car the added clearance adds materially to the free movements and consequently the work efficiency of the operators within the car. The arrangement also actually serves to increase the bag capacity of the rack. At present, four extension bridges, each capable of supporting two bags, are standard equipment in an ordinary thirty foot mail apartment. This make a total

of eight extra full-size bags which may be added to each main rack. Each of the improved extension units provides for mounting three full size bags and because three of the latter extension units may be accommodated in a standard main rack, a total of nine additional bags is provided instead of the eight heretofore available.

The improved rack extension unit, of which the detailed construction and operation has been given above, is, first of all, characterized by simplicity of design as compared with the equivalent assemblage of parts now in general use; embodies no separate parts liable to become detached or lost; may be set up and removed in but a small fraction of the time now required to erect and dismantle its present counterpart and costs materially less to produce than the present apparatus. Of equal importance are its capability of occupying but very little room in storage and of affording a greater degree of room both in front of the rack and below it.

The foregoing disclosure has been devoted to the description of bag supporting racks used in confined apartments such as railway mail cars. However, it will be apparent to those skilled in the art that the features of construction may be applied to other devices and locations wherein the need for a demountable bag rack or support is apparent. Such devices may include bag holding frames for weighing scales, bag fillers and the like and are intended to be covered within the scope of the following claims.

I claim:

1. Apparatus for supporting a container comprising a pair of axially spaced parallel rods, an extension unit comprising a pair of spaced parallel side bars, a rod extending between and connected to one end of each of said side bars, the other end of each side bar having notches therein, the first of said notches opening upwardly at the top of said side bar and the second of said notches opening downwardly in relation to said first notch and extending in a plane substantially tangent to an arc described by the radial spacing between said notches, said second notch being positioned for engagement with one of said parallel rods only upon full engagement of said first notch with the other of said parallel rods, and means carried by one of said parallel rods and by said side bar connecting rod for engaging portions of said container.

2. In a rack structure adapted to support uniformly-sized containers including a pair of spaced rods having thereon means for engaging and suspending a first container above a base surface, an extension rack unit comprising spaced rods and arms having therein interlocking means releasably engageable with the spaced rods of the rack structure, said extension unit being supported in spaced relation to said base surface solely by said rack structure, means on said extension unit for engaging a second container and supporting the latter in proximal relation to the first container, and said extension unit being positioned relative to said base surface to bring the bottom of the second container into engagement with said base surface.

3. In a bag rack having fixed supports, an extension rack adapted to be connected to said first-named rack, said first-named rack and said extension rack being provided with interlocking parts for rigidly but detachably connecting the extension rack to the first-named rack, said first-named rack forming the sole support for said extension rack, and means carried by the first-

named rack and the extension rack for securing the mouth of a bag thereto.

4. In a bag rack having fixed supports, an extension rack adapted to be connected to one of said fixed supports, said first-named rack and said extension rack being provided with interlocking parts for rigidly but detachably connecting the extension rack to the first-named rack, said first-named rack forming the sole support for said extension rack, and means carried by the first-named rack and the extension rack for securing the mouth of a bag thereto.

5. In a bag rack having fixed supports, an extension rack adapted to be connected to said first-named rack, said first-named rack and said extension rack being provided with interlocking parts for rigidly but detachably connecting the extension rack to the first-named rack, said first-named rack forming the sole support for said extension rack, and means comprising rods and hooks on said rods carried by the first-named rack and the extension rack for securing the mouth of a bag thereto.

6. In a bag rack having fixed supports, an extension rack adapted to be connected to said first-named rack, said first-named rack and said extension rack being provided with interlocking parts including spaced notches on said extension rack for rigidly but detachably connecting the extension rack to the first-named rack, said first-named rack forming the sole support for said extension rack, and means carried by the first-named rack and the extension rack for securing the mouth of a bag thereto.

7. In a bag rack having fixed supports, an extension rack adapted to be connected to said first-named rack, said first-named rack and said extension rack being provided with interlocking parts comprising spaced pipes on said first-named

rack and spaced notches on said extension rack adapted to engage said pipes for rigidly but detachably connecting the extension rack to the first-named rack, said first-named rack forming the sole support for said extension rack, and means carried by the first-named rack and the extension rack for securing the mouth of a bag thereto.

8. In a bag rack having fixed supports, an extension rack adapted to be connected to said first-named rack, said first-named rack and said extension rack being provided with interlocking parts comprising spaced pipes on said first-named rack and spaced notches on said extension rack adapted to engage said pipes for rigidly but detachably connecting the extension rack to the first-named rack, said first-named rack forming the sole support for said extension rack, and means comprising a series of hooks mounted on one of said rods and carried by the first named rack, a rod on said extension rack and a series of hooks mounted on said last-named rod, said hooks on both rods being adapted for securing the mouth of a bag thereto.
